Atty.

United States Patent Office.

LEWIS MILLER, OF AKRON, OHIO.

Letters Patent No. 84,433, dated November 24, 1868.

IMPROVEMENT IN MAKING HARVESTER-GUARD FINGERS.

The Schedule referred to in these Letters Patent and making part of the same.

To all whom it may concern:

Be it known that I, LEWIS MILLER, of Akron, in the county of Summit, and State of Ohio, have invented certain new and useful Improvements in Machines for Making Guards or Fingers for Harvesting-Machines; and I do hereby declare the following to be a full, clear, and exact description thereof, reference being had to the accompanying drawings, making a part of this specification, in which—

Figure 1 represents a perspective view of the machine.

Figures 2 and 3 represent, in perspective, and detached from the machine, the rolls and dies for accomplishing part of the work of making and completing the guards.

Figures 4, 5, 6, and 7, represent, in perspective, details of the operation, which will be specially referred to.

My invention consists in the use of special roller-dies, for shaping the parts of which the guards are made, and of welding roller-dies, in connection with die-tongs or holders, for completing the guards by welding and shaping them on the die-tongs or holders.

To enable those skilled in the art to make and use my invention, I will proceed to describe the same by reference to the drawings.

A represents housings, in which are hung and revolved, a pair of rolls, B C, that are geared together, and may be turned, set, or adjusted, in any of the usual well-known ways. The rollers, or their necks or journals, project beyond one of the housings, so that a system of die-rollers may be readily placed and keyed thereon, or removed, and others substituted, as occasion may require. The pairs of rolls are so made, as that a projecting portion of the perimeter of one shall turn in a corresponding depression of the perimeter of its mate or fellow, so as to cause the dies or semi-dies in the pair to match accurately, by preventing any undue end-motion.

The rolls D E, in fig. 1, by their dies a b, roll out a piece or blank like that, F, in fig. 4; and the rolls G H, by their dies c d, fig. 2, roll out pieces or blanks like those, I, at fig. 5. These pieces, being properly heated, the piece F is clamped in a pair of die-tongs or holders, J, fig. 7, one arm, e, of said holder, being

a die or "former," to locate and form the shoulder 1 and the space 2 under the cap, f, of the finished guard or finger, K, fig. 6, and the other arm, g, of said tongs, holder, or former, being a gripping-jaw, to properly hold the said piece F. The piece I, fig. 5, being now laid upon the clamped piece, F, they are subjected, with the tongs, holder, or former, to the welding and shaping-rolls, L M, the dies, h i, of which, not only weld, but with the aid of the shaping-tongs, finish the guard as seen in fig. 6.

The rolls turn toward the operator, and at the front of the rolls there is a table, N, upon which the bar or shaper is rested before entering between the rolls, and for guiding them in being inserted and withdrawn from between the rolls. Behind the rolls there is an adjustable gauge, O, for defining the distance that the bar or shaper shall be introduced, so as to insure the action of the dies upon them.

Suitable grooves, j, are formed in one or both of the rolls of the pairs, so that the article to be acted upon can be inserted between them, clear up to the gauge, before the dies of the pairs seize, shape, and run it out again. And in those, L M, provision is made for allowing the tongs, shaper, or holder, or at least its shaping-arm, e, to enter between its rolls, as it performs an essential element in the welding and final shaping.

Having thus fully described my invention,

What I claim therein as new, and desire to secure by Letters Patent, is—

In combination with the rolls B C, projecting beyond one of their housings, the pairs of changeable die-rollers, with their dies for rolling out irregular, shouldered pieces, F I, as and for the purpose set forth.

Also, in combination with a pair of rolls projecting beyond one of their housings, a pair of welding and shaping-rolls and dies, and a pair of clamping and shaping-tongs or holders, operating together to hold, weld, and shape a guard or finger, substantially as described.

L. MILLER.
